UNITED STATES PATENT OFFICE.

FOSTER F. HILLIX, OF CLEVELAND, OHIO, ASSIGNOR TO WHITE SEWING MACHINE COMPANY, OF CLEVELAND, OHIO, A CORPORATION OF OHIO.

MOTOR ATTACHMENT FOR SEWING MACHINES.

Application filed April 5, 1922. Serial No. 549,830.

To all whom it may concern:

Be it known that I, FOSTER F. HILLIX, a citizen of the United States, residing at Cleveland, in the county of Cuyahoga and 5 State of Ohio, have invented a certain new and useful Improvement in Motor Attachments for Sewing Machines, of which the following is a full, clear, and exact description.

10 This invention relates to motor attachments for sewing machines, and has for its object the provision of a new mounting or manner of supporting the motor from the head by which an exceedingly simple motor 15 support may be utilized, which at the same time brings about a very compact arrangement and an exceedingly efficient driving relation between the friction driving pulley of the motor and the hand wheel of the sewing 20 machine head.

A further object is to provide a mounting which is especially adapted for sewing machines of the portable type, the mounting being of such a nature that when the motor 25 is supported on the head it does not project outwardly beyond the base so as to require any change in or enlargement of the case which is designed to be fitted over the head. Still further the invention aims to provide 30 a mounting wherein the friction driving pulley of the motor may be maintained in good driving relationship with the hand wheel of the head, and which can be adjusted if conditions require, to vary the pressure between the pulley and hand wheel, 35 without altering the position of the motor, or requiring the use of springs to cause the desired frictional engagement between the pulley and hand wheel.

40 Still further the invention aims to provide a driving pulley which has a yieldable frictional driving portion which maintains its shape under high speed conditions and possesses to a very high degree the feature of 45 durability.

The invention may be briefly summarized as consisting in certain novel details of construction and combinations and arrangements of parts which will be described in the specification and pointed out in the appended claims.

In the accompanying sheet of drawings wherein I have shown that embodiment of my invention wherein the attachment is applied to a so-called portable sewing machine,

Fig. 1 is a rear view of the machine with the motor applied in driving relation to the hand wheel, parts being in section; Fig. 2 is an end view looking toward the right of Fig. 1; Fig. 3 is a detail view showing in section the friction driving pulley; Fig. 4 is a face view of the bracket by which the motor is attached to the end of the head; Fig. 5 is a sectional view through the bracket along the line 5—5 of Fig. 4, showing a portion of the head to which the bracket is attached; and Fig. 6 is a plan view of the bracket attached to the head, a portion of the latter being shown in section.

Referring now to the drawings, 10 represents the upright portion of the arm of the head of the sewing machine and 11 the horizontal portion. Likewise 12 represents the hand wheel and 13 the wooden base upon which the head is mounted, the sewing machine shown being a standard sewing machine of the portable type, which when not in use is adapted to be enclosed in a case, and when in use is supported on a table or other convenient support.

For the purpose of electrically driving the sewing machine, I provide my improved motor attachment which includes a small electric motor 14. In this instance the motor is mounted on the upright portion 10 of the arm of the head, and it is arranged beneath the hand wheel alongside the end of the head, slightly to the rear thereof. Further, it will be noted that the motor is supported in inclined position with its axis in an inclined line which intersects and is at right angles to the axis of the shaft on which the hand wheel 12 is mounted. To bring this about the lower end of the motor is extended slightly into a recess 13^a of the base 95 in order that a motor of the size having sufficient power to drive the machine at high speed may be positioned as shown. A further advantage of this feature lies in the fact that a rheostat may be employed with 100 this motor located in the base without requiring any external conductors to connect the motor to the rheostat.

By reference to Figs. 1 and 2 it will be observed that no part of the motor projects beyond the outline or confines of the base 13, so that it becomes unnecessary to enlarge the case in which the head of the machine is designed to be enclosed when the machine is not in use.

This arrangement of the motor allows for an exceedingly simple but efficient supporting or attaching means between the motor and head. This is in the form of a bracket 5 15 which is preferably formed of sheet metal, though it may be formed of cast metal, for with the pulley referred to presently, the bracket need not be of spring material. This bracket has a portion 15^a 10 which lies flat against, and is secured to the head, and in this instance to a flat boss 10^a cast on the end face of the upright portion of the head a short distance above the base 13. This bracket is preferably secured to 15 the boss by a single screw 16 passing centrally through the portion 15^a of the bracket, and the bracket is then held from turning on the boss by a pair of tongues 15^b 20 which are bent inwardly into notches at the top and bottom of the boss 10^a. Additionally the bracket is provided with a laterally offset and downwardly extended portion 15^c which is secured to the frame or body of the motor.

25 In this manner the motor is effectively supported by a bracket which can be produced inexpensively, and which may or may not be of spring material, with the driving member of the motor in proper relation to the hand wheel.

The driving means between the motor and hand wheel is in the form of a tapered friction pulley 17, which is secured on the upper end of the motor shaft 18 in the manner 35 shown in the drawings, the pulley being tapered and engaging the outer side face of the hand wheel rim. It will be obvious therefore, that a proper driving relation 40 between the motor and hand wheel can be obtained by adjusting the pulley lengthwise of the motor shaft and then by securing it in place by means of a set screw 19 or equivalent means. The adjustability of the pulley is particularly useful when a rigid bracket 45 is employed, or if the bracket is formed of spring or elastic material when the spring or elasticity is not relied on to hold the pulley in engagement with the hand wheel.

50 As a further feature of this mounting I have provided a pulley which has noiseless driving engagement with the hand wheel, and which is capable of years of use without requiring replacement, and very little, if any adjustment lengthwise of the motor shaft. 55 The pulley here shown is composed of a body portion 17^a of rubber whose outer periphery is tapered as shown. In forming this pulley opposite sides thereof are squeezed and held between a pair of disks 17^b and 17^c, the former being larger than the latter, and both being preferably concaved inwardly somewhat, substantially as shown in Fig. 3. In this instance the body of rubber 17^a and the clamping disks 17^b and

17^c are slipped onto a sleeve 17^d of a size 65 which will fit onto the motor shaft 18, this sleeve having at one end a shoulder or enlargement 17^e through which the set screw 19 passes. In assembling the parts the disk 17^c is first slipped onto the sleeve and is 70 moved up against the shoulder 17^e. Then the body of rubber and larger disk 17^b are slipped onto the sleeve and the disks are clamped together and the smaller end of the sleeve opposite the shoulder 17^e is peened 75 over or expanded as shown at 17^f to hold the parts in their proper relationship.

The clamping pressure produced on the rubber by the disks 17^c and 17^b bulges out the rubber between the disks and puts it 80 under tension. Then the periphery is cut off, leaving a flat tapered surface which is designed to engage the hand wheel 12. By so forming the pulley, inasmuch as the driving surface is under tension, and has a natural tendency to move inward, the inherent stresses in the rubber resist the action of 85 centrifugal force, and as a result the rubber will not bow outwardly and be displaced by centrifugal force when the motor is operated 90 at high speed. Additionally a very durable wear resisting driving surface is provided.

While I have shown the preferred construction, modifications may be made in the arrangement of certain of the parts without 95 departing from the spirit and scope of my invention. For example, the main features of the mounting may be employed without employing a tapered pulley, and a driving pulley constructed on the principle of that 100 described above may be utilized advantageously with the motor supported on the arm in a different position with respect to the hand wheel.

Having described my invention, I claim: 105

1. In combination with a sewing machine having a head with a hand wheel, a motor, and a bracket securing the motor to the head, said motor having a tapered pulley frictionally engaging the hand wheel and secured on the motor shaft so that it may be 110 adjusted lengthwise thereof to vary the pressure of the pulley on the hand wheel.

2. In combination with a sewing machine comprising a head having a shaft and a hand wheel, a motor attachment comprising a motor supported from the head with its axis at substantially right angles to the axis of the shaft and hand wheel and having a tapered friction driving pulley engaging the hand wheel and secured to the motor shaft so that it may be adjusted lengthwise thereof to vary the pressure between the pulley 115 and hand wheel. 120

125 In testimony whereof, I hereunto affix my signature.

FOSTER F. HILLIX
